UNITED STATES PATENT OFFICE.

JOHN O. NEIKIRK, OF LOMBARD, ILLINOIS, ASSIGNOR TO NATIONAL DUMP CAR COMPANY, OF CHICAGO, ILLINOIS, A CORPORATION OF MAINE.

DOOR-CONTROL MECHANISM.

Application filed June 8, 1921. Serial No. 475,961.

This invention relates to door control mechanism.

The invention is particularly adaptable for use in connection with railway cars and contemplates the operation of a number of doors from one point and with a simple operation.

One object of the invention is to provide a simple and sturdy structure which will be efficient in operation and which will have very little likelihood of getting out of order.

Another object is to provide a railway car with door control mechanism adapted to lock a holding member for a door or holding members for a plurality of doors and to move said holding member or holding members into non-holding position in a manner to meet the requirements of commercial operation.

A further object is to provide door control mechanism having means to lock the holding members of a plurality of doors in door closing position and means for moving said holding members to non-holding position in a predetermined succession of steps, only a simple movement on the part of the operator being required. These and other objects are accomplished by means of the arrangement disclosed on the accompanying sheets of drawings in which—

Figure 1 is a fragmentary side elevation of a railway car embodying my invention.

Figure 2 is a fragmentary transverse sectional view on an enlarged scale of the same car.

Figure 3 is a fragmentary side elevation showing on an enlarged scale certain details of my invention.

Figure 4 is a fragmentary plan view of the structure shown in Figure 1.

The various novel features of my invention will be apparent from the following description and drawings and will be particularly pointed out in the appended claims.

Referring to the figures of the drawings, it will be noted that I have disclosed my invention in connection with a railway car and preferably a car having sides 10 (only one being shown) and a plurality of floor doors 11 which, it will be understood, are pivotally mounted in the usual manner adjacent the center sill structure of the car. Each of the doors 11 has at its outer edge a reinforcing angle member 12. Also secured to each floor door 11 is a bracket 13 which

extends laterally from the outer edge of the car and outwardly with respect to the side 10 of the car. To hold each door 11 in closed position, a link 14 is provided, which is pivotally mounted at its upper end in a supporting member 15 preferably permanently secured to the side of the car 10 by means of rivets 16—16. The lower narrowed portion of the link when in a position for holding associated door 11 in closed position passes under projecting bracket 13 as shown in the figures of the drawing. If some means were not provided for retaining or locking the holding link 14 in a position to hold the door 11 closed, said holding means 14 might swing outwardly thereby releasing its associated door, because of the jarring actions occasioned under service conditions. To prevent accidental opening of the associated door and for locking the holding member 14 in door holding position, I have provided locking means which will now be described.

Extending longitudinally of the car is a rod 17 which is supported to have a sliding movement longitudinally of the car. Said rod 17 has fast thereto a plurality of latch members 18 which are adapted to overlie the link members 14 and to lock said link members in door holding position. A hand lever 19, pivoted at the point 20, may be provided for communicating longitudinal movement to the sliding rod 17. The locking members 18 may all be similarly placed on the sliding rod 17 relative to the links 14—14, whereby a predetermined movement of said sliding rod 17 will move all of said locking members 18 into or out of locking relation with said link members 14—14. Also mounted upon the sliding rod 17 are a plurality of wedging members 21—21. Said wedging members 21—21 are located adjacent to the links 14—14 but are placed on the opposite side from the locking members 18—18, whereby movement in a single direction of the lever 19 will result in withdrawing the locking members 18—18 from engaging position and will move the wedging members 21—21 into wedging relation with the links 14—14, whereby to move said links outwardly to disengage the brackets 13—13.

Preferably the wedging members 21—21 will be variously spaced from the link members 14—14 whereby any one movement of the rod 17 in a right hand direction as

viewed in Figure 1, will result in the operation of link members 14—14 in a predetermined succession. The advantages of this construction will be obvious for the reason that a workman stationed at a part of the car adjacent to the lever 19, may by successive increments in the movement of the lever 19 operate the links 14—14 in succession thereby permitting the exercise of choice of locality where each floor door shall be opened to deposit the material held thereby.

When a car is heavily loaded, considerable pressure is imposed on the link 14 and accordingly considerable effort is required for swinging the link 14 laterally out of engagement with its locking projection 13. My invention facilitates the releasing movement of the link 14 by reason of the wedging action of the members 21—21.

It is seen therefore, that a workman stationed at one part of the car may lock all of the door holding members with one movement of the lever 19 and may move said holding members out of holding position by a simple movement of the lever in the opposite direction. He may dump all of the doors in rapid succession if he so chooses by a single movement of the lever 19, or he may cause the opening of the floor doors at intervals by moving the lever 19 in one direction in successive steps. The latter operation will be useful where material is being dumped into a hopper, the car being moved forward in successive steps as the various dump doors are opened.

It is my intention to cover all modifications of the invention falling within the spirit and scope of the following claims.

What I claim as new and desire to secure by Letters Patent in the United States, is:

1. In combination, a plurality of dump

doors, each of said doors having associated therewith a member for directly holding same in closed position, means for locking said holding members in door holding position and also for moving said holding members into non-holding position, and a single member for operating said moving means to move said holding members to non-holding position in predetermined succession.

2. In combination, a plurality of dump door, each of said doors having associated therewith a member for directly holding same in closed position, combined locking and releasing means for controlling the position of said holding members and common operating means for causing said releasing means to operate in a predetermined succession.

3. In a car, the combination of a dump door, a member for holding said door closed, means for locking said holding member, means for wedging said holding member to nonholding position and common operating means for said locking and wedging means movable longitudinally of the car.

4. In combination, a plurality of dump doors, operating means arranged along said doors, a member associated with each of said doors for latching same in closed position, means controlled by said operating means for locking said latching members in latching position and means mounted on said operating means for moving said latching members to non-latching position, said moving means being located at points to move said latching members in predetermined succession.

Signed at Chicago, Illinois, this 3rd day of June, 1921.

JOHN O. NEIKIRK.
